UNITED STATES PATENT OFFICE.

NAPOLEON WILFRED MORISSETTE, OF COLEMAN TOWNSHIP, ONTARIO, CANADA.

SAFETY CLAMP FOR DIAMOND-DRILL RODS.

Application filed August 3, 1922. Serial No. 579,449.

To all whom it may concern:

Be it known that I, NAPOLEON WILFRED MORISSETTE, a subject of the King of Great Britain, and a resident of the township of

5 Coleman, in the Province of Ontario and Dominion of Canada, have invented certain new and useful Improvements in Safety Clamp for Diamond-Drill Rods, of which the following is a specification.

10 This invention relates to a machine to be used in lowering and hoisting diamond drill rods into holes. The object of the invention is to provide an automatic tool which in the operation of raising the rods from the hole, or into an upper hole, will allow the rods to be hoisted, but which, by the use of bevelled jaws, will automatically grip and hold them from sliding into the hole in down holes or from sliding out of 15 upper holes. The machine thus takes the place of the hand or foot operated clamps or tongs at present used in hoisting drilling rods.

20 In drilling a diamond drill hole it is necessary for the recovery of the core and for changing the cutting bit, to raise the rods from the hole. This operation may be necessary several times a day during the drilling. The raising is done by attaching a hoisting cable or other puller to the end of the rod, projecting from the hole and raising the complete rod. This rod is made up of short 25 lengths. When the second length projects from the hole and the limit of the hoisting space is reached the second length is gripped in the old style by the hand or foot operated clamps or tongs, which this machine now replaces. The hoisting cable is slacked off, the first length of rod disconnected, the 30 hoisting cable attached to the second length of rod and the rod again hoisted. The clamps or tongs prevent the rods from sliding back into the hole, while the hoisting cable is being detached from the first length 35 and attached to the second. The hoisting operation is repeated one length of rod at a time, until the whole rod is removed from the hole. In a hole 500 feet long, using 10 foot lengths, the hoisting operation, the disconnecting from one length of rod and the connecting of the hoisting cable on to the next length would thus be repeated fifty 40 times, the tongs coming into use each time to hold the rods from sliding back into the hole during the disconnecting. These tongs being hand operated, require to be clamped 45

50 by hand to the rod and held clamped by a clip. The tongs coming against the pipe casing of the hole prevent the rod from slipping. The clip has to be released and the 55 tongs unclamped by hand before hoisting. Both of the hand operations present elements of danger, as in clamping the clip may slip or the tongs not take positive hold, in either 60 of which cases the rods may drop into the 65 hole, damaging the diamonds in the bit and causing delay in fishing the rods from the hole. Or in unclamping the tongs the hoisting apparatus may be started before the 70 tongs are loose in which case the operator 75 who stands between the tongs and the hoist may be struck by the tongs and serious injury to operator and machine may result.

This invention, which replaces these 80 clamps or tongs, gets rid of both of these 85 dangers. The jaws of this machine with specially cut teeth, come into action the instant the upward pull on the rods is slackened off. The gripping on the rods is positive and the heavier the downward pull on the 90 rods, the tighter the hold the jaws take on it. When hoisting is again resumed the 95 jaws automatically release their hold with the first upward pull and allow the further raising of the rod, taking hold of the rod again each time as the hoisting tension is released. The invention removes the chances of injury to the operator and eliminates the risk of the rods and diamond bit sliding back 100 into the hole and causing damage and delay. It also proves a great saver of valuable drilling time, easily saving over one third of the time of hoisting rods.

The invention is also used in lowering rods 105 into the hole. In this lowering, smooth jaws without teeth are used. These jaws, controlled by a hand lever manipulated by one hand, allow the rods to slip at any required speed into the hole, and instantly stop and hold the rod while the next length 110 is being screwed on.

With the above and other objects in view the invention consists essentially of the construction hereinafter described and set forth in the following specifications and accompanying drawings forming part of the same. The device is for use with size E diamond drill rods. For larger or smaller sized rods, pipes, etc. to be held by this invention, proportionately larger or smaller sized jaws and holders would be constructed on the same principle as here illustrated.

In the drawings:

Figure 1 is a side elevation of an embodiment of the invention.

Figure 2 is an elevation at right angles to Figure 1.

Figure 3 is a sectional elevation.

Figure 4 is a section on the line 4—4, of Figure 1.

Figure 5 is a section on the line 5—5, of Figure 1.

Figure 6 is a sectional elevation of a modification of the device used for lowering the drill rod.

Figure 7 is a section on the line 7—7, of Figure 2.

Figure 8 is a section on the line 8—8, of Figure 2.

Figure 9 is a perspective view of the clamping jaws.

20 In the drawings, like characters of reference indicate corresponding parts in all the figures.

Referring to the drawings, A is a box shaped casing conveniently in the form of 25 an iron casing having a central opening 10 through which the drill rod is designed to extend, the latter at one end being formed with a constricted neck 11 internally screw threaded and designed to connect with the 30 screw threaded top of the pipe casing B of the diamond drill rod C whereby the casing is firmly supported in position on the top of the rod. The casing A above the neck 11 is rectangular in section. The opposite sides 12 and 13 of the casing are machined to a bevel of about an inch and a quarter to one foot and designed to receive the clamping jaws D and E which are provided on the outer side with a corresponding 35 bevel and on the inner side are either formed with ratchet teeth when the device is used during raising of the drill rod or smooth when used in lowering the drill rod as shown in Figure 6. In Figures 1 to 5 and 9 the

40 jaws are shown with ratchet teeth 14 on the inner side, the teeth being cut to suitable angles such as angles of 45 degrees and 27 degrees, the sharper angle being on the holding side. The jaws are further curved on 45 the inner side to suit the curvature of the drill rod. The outward movement of the jaws is designed to be limited by suitable means such as by a fork pin F of steel or the like which extends through suitable 50 perforations in the casing A and is designed to abut the shoulders 15 formed on the jaws D and E, by which the outward movement of the jaws is limited. When the shoulder 55 abuts the fork pin F the rod C will be 60 loosed from the clamp and may be freely withdrawn and this is the position while the rod is being pulled upwardly. When, however, the pull on the rod is slackened, the 65 jaws D and E will drop and the bevel on the casing will cause them to move inwardly

and to firmly grip the rod and prevent it from slipping into the casing pipe B.

To enable the jaws D and E to be readily removed should they become stuck in holding position, recesses or holes 16 are bored 70 in them towards the outer end and in which a suitable tool may be inserted to withdraw them.

When the device is to be used for lowering the rod, the toothless jaws D¹ and E¹ 75 are used, in the form shown in Figure 6. These jaws being provided with smooth curved inner faces 17 which fit closely to the drill rod C and with bevelled outer faces 18 which fit the bevels 12 and 13 on the 80 casing. The jaws in this instance are not automatic in their action and suitable clamping means are provided on the casing by which they may be tightened in position, these means comprising a cam 19 formed on 85 a cross shaft 20 journaled in lugs 21 on the casing, the shaft being designed to be turned by suitable means such as a lever handle 23 which may have detachable engagement 90 with the hexagonal or squared end 24 of the shaft 20. It may also be noted that the cam 19 may be used if desired to give additional gripping action to the toothed jaws D and E. When used with the smooth jaws D¹ and E¹ the pressure of the cam will 95 produce sufficient friction either to hold the rod C in place or allow it to lower through the clamp at any required speed.

From the foregoing, it will be seen that I have invented a safety clamp for diamond 100 drill rods etc. which is easily constructed and securely fastened to the ordinary pipe casing and will occupy a minimum space and when in position may be readily brought into and out of operation. In the hoisting 105 operation, the hold on the rod is automatic, whereas in lowering the rod the pressure may readily be applied by operation of the lever 23.

As many changes could be made in the 110 above construction and many widely different embodiments of my invention within the scope of the claims, constructed without departing from the spirit or scope thereof, it is intended that all matter contained in the 115 accompanying specification and drawings shall be interpreted as illustrative and not in a limiting sense.

What I claim as my invention is:

1. A clamp of the character described comprising a casing having a threaded neck designed to engage the top of the casing of a diamond drill rod, the diamond drill rod being designed to pass through the casing, bevel faces formed on the inner side of the casing, a pair of bevel jaws mounted in the casing and designed to grip the drill rod, and means for limiting the outward movement of the said jaws, the said means comprising a spring fork extending transverse- 130

ly through the casing and shoulders on the jaws designed to engage the fork.

2. A clamp of the character described comprising a casing having a threaded neck 5 designed to engage the top of the casing of a diamond drill rod, the diamond drill rod being designed to pass through the casing, bevel faces formed on the inner side of the casing, a pair of bevel jaws mounted in the 10 casing and designed to grip the drill rod, a spring fork extending transversely through the casing, shoulders on the jaws designed to engage the fork, and cam means designed to force the jaws against the rod.
- 15 3. A clamp of the character described comprising a casing having a threaded neck designed to engage the top of the casing of a

diamond drill rod, the diamond drill rod being designed to pass through the casing, bevel faces formed on the inner side of the 20 casing, a pair of bevel jaws mounted in the casing and designed to grip the drill rod, a spring fork extending transversely through the casing, shoulders on the jaws designed to engage the fork, a cross shaft in the 25 casing, a cam on the cross shaft, and a lever handle connected to the shaft designed to force the jaws against the rod.

In witness whereof I have hereunto set my hand in the presence of two witnesses. 30

NAPOLEON WILFRED MORISETTE.
